UNITED STATES PATENT OFFICE

LEIF LEE, OF YOUNGSTOWN, OHIO

PICKLING APPARATUS

Application filed October 10, 1930. Serial No. 487,745.

This invention provides an apparatus for pickling pipe or other fabricated forms of material and the like and particularly an apparatus which will thoroughly and efficiently complete the pickling operation in a minimum time.

Pipe, for example, has been comparatively difficult to pickle successfully due to its attenuated form and its comparatively inaccessible inner-surface with the result that such pickling has hitherto been relatively incomplete and unsatisfactory with detrimental results of a serious nature. Other materials and shapes present similar or analogous difficulties.

One of the objects of the present invention is to provide a pickling apparatus for pipes and the like which will thoroughly and quickly completely pickle the same at every available portion of its surface.

Another object is to provide an apparatus whereby the material is completely pickled by moving it back and forth in the pickling fluid so that the latter reaches every portion of the surface of the same both interior and exterior.

A further object is to provide an articulated framework having non-rigid connections so that a material supporting tray associated therewith may be suitably moved in the pickling fluid.

A further object of this invention, therefore, is to provide such a pickling apparatus as will enable the material to be pickled to be given a predetermined movement in the pickling fluid so that the latter quickly and completely reaches all portions of the inner and outer surfaces of the same.

A further object is to provide for the straight line movement of the material in the pickling fluid.

A further object is to enable the material, when so desired, to be given a curvilinear or arcuate movement which has been found to be extremely efficient under certain circumstances and conditions.

Other and further objects will either be understood by those skilled in this particular art or will be pointed out hereinafter.

A preferred embodiment of the invention

has been illustrated in the accompanying drawings wherein:

Figure 1 is a plan view of one form of the invention.

Fig. 2 is a sectional elevation on the line II—II of Fig. 1.

Fig. 3 is a transverse sectional elevation on the line III—III of Fig. 1.

Fig. 4 is a side elevation of the means for connecting a framework and pipe supporting tray.

Fig. 5 is a view taken at right angles to Fig. 4.

Fig. 6 is a side elevational view of one of the articulated uprights.

Fig. 7 is an elevational view partly in section at right angles to Fig. 6.

Fig. 8 is a plan view of another form of the pickling apparatus.

Fig. 9 is a transverse sectional elevation on the line IX—IX of Fig. 8.

Fig. 10 is a side elevational view of the apparatus of Fig. 8.

Fig. 11 is a cross section on the line XI—XI of Fig. 10.

Fig. 12 is a detail of a modified form of guideway, and

Fig. 12a is a detail of a further modified form of guideway.

Similar numerals refer to similar parts throughout the several views.

Referring first to Figs. 1 to 7, inclusive, the numeral 10 indicates a fragmentary portion of a suitable pit which may be constructed of any suitable material and in the bottom of said pit are the supporting beams 11 upon which rests a vat 12 or other suitable tank or receptacle, which may be composed of any suitable material resistant to the action of the pickling fluid adapted to be contained therein and which latter may be any of the usual pickling fluids depending upon the circumstances and conditions involved or to be met, respectively.

Suitably suspended in said vat is the material supporting tray 13 having partition members 14, if required, for supporting a plurality of rows of material in each of which row may be a number of pipe sections or other articles or material superposed on

each other. This tray 13 is connected, as shown in Figs. 4 and 5, to a supporting framework 15 which may consist of suitable I-beams or the like and the manner of connecting said tray and said I-beams forms no part of the present invention as it is old and well known in this art. Briefly, it consists of a diagonal rod member 16 connected to each corner of the tray by means of a suitable U-bolt construction 17 passing through an eye 18 in the lower end of the rod. The upper end of the rod is formed with a larger eye 19 which is connected to the pin clamp assembly 20 so as to permit of the tray being swung. It can be suitably swung or moved by an appropriate movement of the supporting framework 15 as will hereinafter more fully appear.

The ends of the supporting framework 15 are preferably provided with a suitable roller construction 21, as shown in Figs. 6 and 7. This roller construction is adapted to fit comparatively loosely into the upper end of the articulated upright 22, a socket 23 at the upper end thereof being provided for such purpose. The lower end of the upright 22 is pin connected to a suitable base member 24 at 25 associated with a portion of the pit 10 such as the shelf 26 thereof, as clearly shown in Fig. 3.

Two of these base members 24 are provided, one on each side of the vat 12 and each base has two uprights 22 extending from the ends thereof so that the four ends of the two I-beams of the supporting framework 15 are adapted to rest within the socketed ends of the four articulated uprights. Intermediate their length, the uprights are suitably interconnected as shown in Figs. 6 and 7 by a connecting rod 27 thereby maintaining said uprights in fixed relationship to each other and maintaining them always in such relationship that when they move they maintain their parallelism. As clearly shown in Figs. 1 and 2, connecting rods 28 are provided between the last uprights and a crank shaft 29 to which they are so connected that upon the actuation of the crank shaft by means of the prime-mover or source of power 30, which may be an electric motor, acting through friction clutches 31 and the reducing gears 32, causes said connecting rods to move eccentrically, causing, in turn, the uprights 22 to pivot at their pin connection 25 with the base members 24 and to describe the arc subtended by the angle α , the movement constituting that limited by the aforesaid angle. The crank shaft 29 is suitably supported in bearings 33 supported by a shelf 34 of the pit, as shown in Figs. 1 and 2.

When the aforesaid movement is imparted to the uprights 22 by means of the connections therewith of connecting rods 28, the rollers 21 of supporting framework 15 move within said sockets 23 so as to provide a non-

rigid or yielding connection, that is, one which will not interfere with the movements above described. The supporting framework is, however, given a limited movement in this manner which is imparted to the material supporting tray 13 so as to cause the same to move back and forth in the pickling fluid in vat 12, thus causing the pickling fluid to be surged back and forth vigorously and through or about the material, thus completely reaching the entire inner and outer surfaces of the material and completing the pickling action in a minimum time due to the constant agitation of the pickling fluid and the resultant reaching of the surfaces of the material by new unexpended fluid.

The supporting framework 15 is suitably interconnected by the framework 35 and is provided with an apertured extension 36 so that a crane or other lifting device, not shown, may be readily utilized to lift the tray full of material out of the pickling fluid so that it may be unloaded and a new supply substituted, the roller and socket connection between the upper end of the articulated upright, and the ends of the supporting framework being readily disengageable so that no connections prevent the simple lifting off of the supporting framework with its attached tray, with or without the material thereon.

Coming now to Figures 8 to 12, inclusive, I provide a source of power 10' which actuates a crank shaft 11' to which are eccentrically connected at each end thereof a pair of connecting rods 12' suitably connected to movable elements 13' associated with a supporting framework 14', from which depends a pipe or other material supporting tray 15', thereby enabling the latter to be suitably moved in a pickling fluid for the purposes of efficiently and completely pickling the material contained on said tray.

I provide a pit 16' of suitable type and construction and supported therein as by supporting blocks 17' is the vat 18' of any suitable or desired construction and adapted to contain a pickling fluid, which latter may be any of the usual fluids generally utilized for such purposes and well known in the industry.

Suspended in said vat is the material supporting tray 15' provided with upstanding partition members 19' for the usual purposes, the tray being connected by means of rods 20', for example, to the supporting framework 14' composed of a suitable I-beam construction and provided with the portion 21' so that the supporting framework and tray may be all lifted or otherwise transported by a suitable crane or other lifting device, not shown, as more fully explained above aenit Figures 1 to 7, inclusive.

The supporting framework 14' is constructed as shown in Fig. 8 and, as stated, includes two transverse I-beams the ends of

which rest in socket members 22' suitably connected with the movable elements 13' which may terminate in sleeves 24' in which are rotatably mounted in the case where a 5 rotatable member is used, the shafts of rollers 25'. These rollers are adapted to operate in guideways 26' in framework 27' supported on supports 27" on shelf 27''' of pit 16', all arranged as shown in Figs. 10 and 11, the 10 guideways or slots 26' being horizontal, and both guiding and limiting the movement of the rollers 25' and hence the movement of the material supporting tray 15'.

The sleeves 24' in which the shafts of rollers 25' operate have projections 28' in which are pin-connected the connecting rods 29', one sleeve having a similar formation 30' diametrically opposite, to which is also pin-connected the connecting rod 12' eccentrically 20 connected, as shown in Fig. 11, with the shaft 11' which is supported in bearings 31' and actuated through the source of power 10' and the reduction gearing 32' and friction clutches 33'.

25 It will thus be seen that when the source of power is turned on, the rollers will be caused to roll back and forth in slots 26' in framework 27' through the actuation of connecting rod 12' and a suitable movement will, 30 therefore, be given to the material supporting tray 15' and hence pickling fluid will be surged vigorously back and forth through and over the material thus thoroughly and completely pickling the same in the 35 minimum time with the maximum of efficiency.

I have discovered further that if the rollers are caused to describe a curvilinear or arcuate path instead of a straight line path in a 40 horizontal direction, even greater efficiency will be obtained and the additional stirring up of the pickling fluid will enhance the effect by even further diminishing the time and increasing the action. This curvilinear or arcuate movement can readily be obtained 45 by configuring the slots 26' or framework 27' in the form shown in Fig. 12, wherein the slots 26'' are curved, thus imparting a corresponding motion to the pipe supporting tray.

50 It is not necessary that rollers be provided as I find that satisfactory efficiency can be as readily obtained with any suitable sliding members which need not roll and hence which need not be so mounted as to enable 55 them to roll. In this connection, reference is had to Fig. 12a, wherein is shown guideways 27a' provided with slots 26a' which are straight-line slots. Slidable blocks or other suitable members 25a' operate in slots 26a' 60 by sliding back and forth therein as will be understandable from the foregoing. If necessary or desirable, these sliding members may be lubricated suitably and composed of any preferred material. In this way, I provide a substantially equally satisfactory

means for moving the material supporting tray in the pickling fluid in the vat, this construction being much simpler, therefore, and hence less likely to need attention or repairs. If found desirable or necessary the 70 guideways may be slightly greased to enable the sliding member to pass back and forth readily without generating too much friction or too much heat and hence without putting too much of a load upon the source of power and its connections, although the source of power and connections are, of course, designed to take care of loads substantially in excess of what they are likely 75 to be required to withstand.

80 It is understood that the above is more illustrative than limitative and that I may vary the connections and details to suit the particular requirements of any batch of material and that any such changes, substitution, additions or omissions fall within the spirit and scope of my invention.

85 What I claim as new and desire to secure by Letters Patent is:

1. In a pickling apparatus, a pit, a vat 90 in said pit, a framework above said pit and vat, a material supporting tray depending from said framework, and means associated with said pit for maintaining said framework in position, said means including a 95 base, a pair of uprights pin-connected thereto, the tops of said uprights non-rigidly receiving said framework, connecting rod means attached to said uprights intermediate their ends, and means for eccentrically 100 actuating said connecting rod means.

2. In a pickling apparatus, a pit, a vat in said pit, a material supporting tray in said vat, an overhead framework from which said tray depends, and means for maintaining said framework in position, said means including a pair of bases associated with said pit on opposite sides of said vat, a pair of uprights pin-connected to each base, the tops of said uprights and the ends of said framework being non-rigidly connected to permit relative movement therebetween, and connecting-rod means intermediately connected to said uprights, there being means for eccentrically actuating said connecting rods. 105

110 3. In a pickling apparatus, a pit, a vat in said pit, a material supporting tray in said vat, an overhead framework from which said tray depends, and means for maintaining said framework in position, and means including a pair of bases associated with said pit on opposite sides of said vat, a pair of uprights pin-connected to each base, the tops of said uprights and the ends of said framework being non-rigidly connected to permit relative movement therebetween, and connecting-rod means intermediately connected to said uprights, there being means for eccentrically actuating said connecting rods, 115 120 the tops of said uprights having sockets for 125 130

the reception of the ends of said framework and said ends being provided with rollers for cooperation with said sockets.

4. In a pickling apparatus, a material supporting tray, a framework for suspending said tray in a pickling fluid, a supporting framework for said first framework, said frameworks having a non-rigid connection, and said supporting framework being pivotable near its lower end, there being eccentric means connected to said supporting framework to move the same through a predetermined angle, thereby, through said first framework, transmitting a predetermined movement to said tray.

5. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a path determined by said slots, said guideways having underlying supports, said supports resting on the shelf of an associated pit.

6. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a predetermined path, the slots of said guideways being arcuate and the movement of said tray therefore corresponding thereto, said guideways having underlying supports, said supports overlying the shelf of an associated pit.

7. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a predetermined path, said members being rolling elements, interconnected to each other and to said means said guideways having underlying supports, said supports overlying the shelf of an associated pit.

8. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a predetermined path, said

members being sliding elements, interconnected to each other and to said means.

9. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a predetermined path, said members being rolling elements, interconnected to each other and to said means, the slots of said guideways being arcuate and the movement of said tray, therefore, corresponding thereto, said guideways having underlying supports, said supports overlying the shelf of an associated pit.

10. In a pickling apparatus, a pair of guideways, said guideways being slotted, members adapted to operate in the slots of said guideways, a framework associated with said members, a material supporting tray suspended from said framework, and means for causing said members to operate in said slots and hence, through said framework, said tray to move in a predetermined path, said members being sliding elements, interconnected to each other and to said means, the slots of said guideways being arcuate and the movement of said tray, therefore, corresponding thereto.

In testimony whereof, I have hereunto subscribed my name this 8th day of October, 1930.

LEIF LEE.
